INVENTOR.

UNITED STATES PATENT OFFICE.

JOHN BUSACKER, OF UTICA, NEW YORK, ASSIGNOR TO TUCKER, CALDER & CO., OF SAME PLACE.

DOUBLE FLAT BINDERS.

SPECIFICATION forming part of Letters Patent No. 328,646, dated October 20, 1885.

Application filed February 23, 1884. Serial No. 121,657. (Model.)

To all whom it may concern:

Be it known that I, JOHN BUSACKER, of the city of Utica, county of Oneida, and State of New York, a citizen of the United States, 5 have invented a new and useful Improvement in Double Flat Binders; and I do hereby declare the following to be a full, clear, and exact description of the same, reference being had to the accompanying drawings, and to the letters 10 and figures marked thereon.

My invention relates to a cheap and efficient mechanism adapted to apply and attach double flat binding to coats, vests, and a variety of other classes of work where double flat binding is used, and is adapted to be used in connection with any sewing-machine, and is attached to the presser-foot bar of an ordinary sewing-machine, and when so applied and used as hereinafter described it applies a 15 double flat binding to the edges of a garment by guiding the same so that one edge of both bindings may be stitched in one operation.

Having described the general purpose of my invention, I will now proceed to describe 20 it by reference to the accompanying drawings, in which—

Figure 1 represents a perspective view of my improved binder on a section of the cloth-plate of an ordinary sewing-machine and a 25 section of the head and arm of an ordinary sewing-machine with a needle and presser-foot working in the head. Fig. 2 represents a top view of my improved binder. Fig. 3 represents a side elevation of the same. Fig. 4 30 represents an end elevation of the same. Fig. 5 represents a top view of the presser-foot and plate of my improved binder. Fig. 6 represents a side elevation of the same. Fig. 7 represents an end elevation of the same. Fig. 7 35 represents a top view of the adjustable cloth-guide. Fig. 9 represents a side elevation of the same. Fig. 10 represents the opposite side of my improved binder from that illustrated in Fig. 3, showing a coil-spring between the plate, Fig. 5, and the adjustable cloth-guide Fig. 8, also an end view of the movable binding-guard, with a spring between it and the adjustable cloth-guide, Fig. 8. Fig. 11 represents an end view of the cloth-guide. Fig.

12 represents a perspective view of the stop 50 S, which holds, as shown in Fig. 2, the adjustable cloth-guide, Fig. 8, and by means of it and an adjusting-screw a lateral adjustment is secured. Fig. 13 represents a perspective view of a movable binder-guard. Fig. 14 55 represents a perspective view of the upper adjustable binding-guide. Fig. 15 represents a perspective view of the lower binding-guide. Fig. 16 represents a portion of the presser-foot and plate cloth-guide with a spring be- 60 tween, and an end view of the supplemental movable binder-guard with coiled spring b' between it and the cloth-guide, on a larger scale than Fig. 10, with parts broken away, and taken on line z z of Fig. 2 through the 65 grooves a' and b', that receive the upper and lower binding-guides, e and e'.

Having described my invention by reference to the figures marked on the accompanying drawings, I will now proceed to describe 70 the same by reference to the letters marked thereon, in which similar letters refer to corresponding parts throughout the several views.

A represents a section of the top of the cloth- 75 plate of an ordinary sewing-machine.

A' represents a section of the head of an ordinary sewing-machine.

A² represents a section of the arm of an ordinary sewing-machine, to which the head is 80 attached.

A³ represents a needle-bar with a needle therein.

A⁴ represents a bar carrying the presser- 85 foot and plate.

a represents the presser-foot and plate of my improved binder.

a' represent two longitudinal slots in the presser-foot plate.

a² represents a central slot in the presser- 90 foot plate.

a³ represents a longitudinal groove on the front surface of the presser-foot plate for the reception of the upper binding-guide. This slot is on an incline, as indicated in Fig. 7, to 95 give the proper pitch to the binding-guide to bring the binding under the presser-foot and needle of the sewing-machine.

*a*⁴ represents an aperture for attaching the presser-foot plate to the bar.

*a*⁵ represents a circular aperture in the presser-foot plate, through which the needle 5 moves.

b represents an adjustable cloth-guide. The office of this guide is to guide and even the edges of the binding and cloth to secure an even and uniform application of the bindings 10 to the cloth.

b' b' represent two projecting ears on the cloth-guide, which fit into the slots *a' a'* in the presser-foot plate.

b' represents circular holes on the tops of 15 the lugs for the reception of a pin.

b' represents a pin inserted in the holes *b'*, by means of which the presser-foot plate and cloth-guide are held together loosely, and thus giving to the latter slight vertical and lateral 20 play. By locating the holes in the upper portion of the projections *b' b'* in the cloth-guide slight vertical play is secured to the presser-foot plate.

*b*⁴ represents a coil-spring between the cloth- 25 guide and presser-foot plate for securing a vertical automatic adjustment of the presser-foot plate and cloth-guide as the machine is operated to allow the cloth to pass more freely between the upper and lower binding-guides.

30 A lateral adjustment of the cloth-guide is secured by loosening the screw *d*, which works in a slot, *a*², which, when loosened, allows the ears *b' b'* to move in slots *a' a'* to the required distance. Then the screw is tightened.

35 *S* is a stop which is attached to the lower part of the presser-plate by the set-screw *d*, which holds it in place, and which facilitates the lateral adjustment of the presser-plate with relation to the needle according to the 40 distance which it may be desired to leave between the edge of the article to be bound and the row of stitches, all of which will depend upon the width of the braid to be attached. The object of this adjustment is to secure the 45 application of the bindings to the cloth at the proper place, to secure even and uniform work, and to accommodate different widths of binding, and to guide the cloth and binding under the needle by keeping the edges of the cloth 50 and binding close up against it.

*b*⁵ represents a depressed or rabbeted surface on the cloth-guide.

55 *b*⁶ represents a projecting guide-post, which extends above and in front of the presser-foot plate, as indicated in Fig. 3.

*b*⁷ in Figs. 8, 9, and 16 represents a cross-groove on the under side of the cloth-guide, adapted to receive the lower binding-guide.

60 *b*⁸, Fig. 8, represents a hole in the cloth-guide for the reception of the pin *c* on the binding-guard *C*, Fig. 13.

65 *c*, Fig. 13, represents a supplemental movable guard with a stationary pin, *c'*, in the center. This binding-guard is placed on the rabbeted surface of the cloth-guide at *b*⁵, Fig. 8, with a pin inserted in the hole *b*⁸. One or more coil-springs, *c*² *c'*, are placed between

this binding supplemental guard and the surface of the cloth-guide. These springs keep this guard in contact with the presser-foot 70 plate by causing it to move up and down with the presser-foot as the machine is operated. The sole office of this guard is to prevent the edges of the binding and cloth from getting between the cloth-guide and the presser-foot 75 plate when in use. It is obvious that this vertically-reciprocating guard would perform its functions in a single or double binding guide attachment.

e represents the upper binding-guide. *e'* 80 represents a slot for adjusting the same by means of screw *e*³, Fig. 2.

*e*⁴ represents a longitudinal slot in the end of the binding-guide of sufficient length and breadth to accommodate ordinary flat binding. This binding-guide is placed in groove *a*³, Fig. 1, and is held in place and adjusted laterally by means of set-screw *e*³, Figs. 1 and 2.

*e*⁵ represents the lower binding-guide. *e'* 90, Fig. 15, represents a longitudinal slot by means of which, in connection with a set-screw similar to *e*³ in the upper binding-guide, a lateral adjustment to the width of the binding-guide is secured.

*e*⁷ represents a longitudinal slot in the end 95 of the lower binding-guide, *e'*, with sufficient length and breadth to accommodate ordinary binding. This binding-guide is placed in cross-groove *b*¹, Fig. 9, on the under side of the cloth-guide, and is adjustable laterally, as 100 before described. Both binding-guides are substantially alike, and are each adapted to receive and guide a single flat binding under the presser-foot and to the needle of a sewing-machine upon opposite sides of the cloth, 105 to which the said flat bindings are to be applied. The upper binding-guide, Fig. 14, is attached to the top of the presser-foot plate, and the lower binding guide, Fig. 15, is attached to the lower surface of the cloth-guide, as shown, 110 ready for operation in Fig. 1. The binding-guides are attached to the presser-foot plate and cloth-guide. They may be attached to the presser-foot plate.

Operation: My improved double flat binder 115 is attached to the presser-foot bar of the ordinary sewing-machine. The binding is inserted in slots *e' e'*. The cloth to which it is to be applied is placed between the binding-guides with the cloth-guide adjusted to regulate the proper application of the binding to the material and the cloth, and two bindings are brought under the presser-foot, which brings the same in contact with the feed-motion, which feeds the same into the machine, 120 and the two bindings and the cloth are guided evenly, thereby applying the two bindings to the edge of the cloth in one operation. The extreme outer edges of the two bindings can then be sewed together, or to the garment in one 125 operation, if the operator wishes to so unite them.

What I claim as new, and desire to secure by Letters Patent, is—

1. The herein - described double - binding guide attachment for sewing-machines, having a presser-foot plate, an upper binding-guide with elongated slot for guiding a flat binding to the upper surface of the cloth carried by the presser-foot plate, a cloth-guide for guiding the cloth, a lower binding-guide with an elongated slot attached thereto for guiding a flat binding to the under surface of the cloth, the presser-foot plate and cloth-guide so adjusted as to allow the cloth to pass between the guides, a guard for preventing the cloth and binding from getting between the cloth-guide and the presser-foot plate, combined and arranged substantially as described for applying separate flat bindings to the opposite surfaces of cloth, substantially as described. 5
2. The herein - described double - binding guide attachment for sewing-machines, having a presser-foot plate, an upper binding-guide with an elongated slot for guiding a flat binding to the upper surface of the cloth carried by the presser-foot plate, an adjustable and movable cloth-guide for guiding the cloth attached to the presser-foot plate to allow the cloth to pass between the guides, a lower binding-guide with an elongated slot attached to the cloth-guide for guiding a single flat binding to the under surface of the cloth, a movable guard for preventing the cloth and binding from getting between the cloth-guide and the presser-foot plate, combined and arranged substantially as described for applying double flat bindings to the opposite surfaces of cloth, as described. 10
3. In a double-binding guide attachment for sewing-machines, the independent upper and lower binding-guides, each of which has the closed slot, as above described, which accommodates and supports in the same horizontal plane both edges of a separate binding, in combination with a presser-foot having a slotted extension-plate and adapted to be secured to the presser-bar of a sewing-machine, and the lower slotted plate hinged to said presser-foot. 15
4. In a double-binding guide attachment for sewing - machines of the character described, a cloth-guide, a presser-plate, and presser-foot, two independent longitudinally-slotted binding-guides e and e' , having closed slots, as described, each of which accommodates and entirely surrounds an independent binding, in combination with an automatically-self-adjusting guard which prevents the cloth and binding from getting in between the cloth-guide and presser-foot of a sewing-machine while in operation. 20
5. In a double-binding guide attachment for sewing - machines of the character described, two independent binding-guides, each of which is independently adjustable laterally and accommodates and supports a separate binding in a continuous unbroken elongated hole in each of their free ends, whereby a narrow binding may be attached to one side of an article and a wide binding to the other side of said article. 25
6. In a binding-guide attachment for sewing-machines, a presser-foot having presser-plate extension and binding-guide, in combination with a cloth-guide provided with an automatically-self - adjusting vertically - reciprocating guard. 30
7. In a binding guide-attachment for sewing-machines, the presser-foot having presser-plate extension provided with an independent upper binding-guide and provided with slots for the reception of projections on the upper face of a cloth-guide, in combination with a cloth-guide provided with upwardly-projecting perforated projections, and a pin for pivotally securing the presser - foot and cloth-guide together. 35
8. In a double - binding guide attachment for sewing-machines, a cloth-guide provided with an independent lower binding-guide and upwardly-projecting projections, the combination of a presser-foot provided with an independent upper binding-guide, slots a a' for the reception of projections on the cloth-guide, and also provided with a slot, a'' , for the reception of an adjusting device whereby a stop, S , is secured at any desired adjustment, and a stop whereby the distance between the needle and the cloth-guide is determined. 40

Signed in the city of Utica, county of Oneida, and State of New York.

JOHN BUSACKER.
